UNITED STATES PATENT OFFICE.

PATRICK E. WOODS, OF BUFFALO, NEW YORK.

GREEN-SAND-CORE BOX.

SPECIFICATION forming part of Letters Patent No. 763,138, dated June 21, 1904.

Application filed July 17, 1903. Serial No. 165,978. (No model.)

To all whom it may concern:

Be it known that I, PATRICK E. Woods, a citizen of the United States, residing at Buffalo, in the county of Erie and State of New York, have invented new and useful Improvements in Green-Sand-Core Boxes, of which the following is a specification.

This invention relates more particularly to a core-box for forming green-sand cores to be employed in molding car journal-boxes.

The object of the invention is to provide a core-box of simple and practical construction in which the green-sand cores can be made rapidly and from which they can be readily removed without injuring them.

Another object of the invention is to form the core-box of the minimum number of separable parts in order to save time in assembling the parts preparatory to forming the core and to avoid injury to the core in moving the parts to free the core and permit its removal from the core-box.

Another object of the invention is to avoid inaccuracies in the formation and location of the hinge-lug for the journal-box lid by providing the core-box with means for supporting the dry-sand mold which forms the hinge-lug on the core-box and making the same a part of the core.

In the accompanying drawings, consisting of two sheets, Figure 1 is a side elevation of a core-box embodying the invention. Fig. 2 is a plan view thereof. Fig. 3 is an end elevation thereof. Fig. 4 is a transverse vertical section thereof in line 4-4; Fig. 2, showing by dotted lines the sides partially opened. Fig. 5 is a perspective view showing the box open and a completed core in place on the bottom. Fig. 6 is a perspective view of the core-support. Fig. 7 is a horizontal section through the rear end of the core-box, showing the removable supporting-slides for the dust-guard-chamber core. Figs. 8 and 9 are vertical sections, on an enlarged scale, of the support for the hinge-lug mold in lines 8-8 and 9-9, respectively. Fig. 2, Fig. 10 is a transverse vertical section of the core-box in line 10-10, Fig. 1.

Like letters of reference refer to like parts in the several figures.

A represents the bottom or base of the core-box, which consists of a bottom plate or portion *a* and downwardly-extending flanges or supports for the bottom plate, which is thus elevated from the floor or support on which the base rests. The upper or inner face of the central portion of the bottom plate *a* of the base is shaped to properly form the bottom face of the core and support the latter and varies somewhat in core-boxes used for making cores for different styles of axle-boxes. The base is also provided at its front end with a transverse horizontal portion *c* and at its rear end with a concaved portion *d*, which constitute seats for the front and rear bearing-shells for the core arbor or support.

F represents the sides of the core-box. The inner faces of the central portions of the sides are shaped to properly form the vertical sides of the core, and, like the bottom plate, vary somewhat in core-boxes for forming cores for different styles of axle-boxes. The front and rear end portions *e* of the sides extend over the front and rear seats *c* and *d* for the core-support. The sides are provided at their lower edges with depending hinge-lugs *f*, which extend inwardly, beside outwardly-projecting hinge-lugs *f'* on the base, to which they are hinged by pins or bolts *f''*. This manner of hinging the sides permits the same to be swung outwardly and downwardly away from the base and the core supported thereby, as indicated in Fig. 5, until they rest upon the surface supporting the core-box. Each side is provided at its ends with transversely-extending upright end sections *G*, which meet over the core-support seats at the ends of the base and constitute the end walls of the core-box. The meeting upright edges of the end sections are preferably provided with co-operating tongues and grooves, (see Fig. 2,) which interlock to prevent endwise play of and insure the proper position of the ends and sides. The sides are held in their upright position and prevented from separating when tamping the sand in the box by a catch *h* at each end of the box pivoted to one end section and engaging a projecting lug *h'* on the other end section. Any other suitable holding devices may be employed. Each side is provided with

along its upper and lower longitudinal edges with inwardly-projecting fillets γ , respectively, which form rounded corners on the core. The fillets at the upper edges of the 5 sides necessarily have thin edges, and they are preferably made separately from the sides of hard metal which will not be easily broken if struck by the tamping-tools in forming the core. As the fillets are on the sides of the 10 box, they are moved away from the core when the box is opened and cannot break the corners of the core when the latter is lifted off of the bottom plate.

The dust-guard chamber of the ear-axle box 15 is formed by a baked-sand core in the form of an upright thin slab K, Figs. 5 and 6. The dust-guard-chamber core is supported in proper position in the core-box, as follows: Each side of the core-box is provided with 20 parallel plates L, which are secured or formed thereon and project inwardly from the upper portions thereof. M, Figs. 4, 7, and 10, represents slides, which project into the core-box below the plates L through vertical openings 25 m in the sides of the core-box. The slides are movable in and are guided by a transverse groove m' in the bottom plate. Each slide consists of two separated parallel plates, which, together with the plates L, projecting 30 from the sides of the core-box, form transverse partitions, which extend from side to side of the core-box and between which the dry-sand core for the dust-guard chamber is supported. The slides M are provided at 35 their outer ends with suitable portions which project outwardly from the box and serve as handles for the slides. The meeting vertical edges of the slide-plates and plates L on the sides of the core-box are preferably provided 40 with interlocking tongues and grooves to hold the opposite plates in alinement.

N, Fig. 6, represents a core support or arbor, which is arranged longitudinally in the core-box and is supported by bearing shells 45 or blocks n n' at the opposite ends of the support and resting on the seats c d at the opposite ends of the base. The core-support is preferably of the construction shown, consisting of horizontal hollow end portions n^2 , 50 which are connected by a plurality of substantially parallel separated grate-bars n^3 . These grate-bars extend downwardly between the ends of the support, so as to conform substantially to the shape of the bottom and 55 lower end portions of the core and when in position in the core-box extend down to within a short distance of the bottom of the core-box. The horizontal hollow end portions of the core-support are comparatively wide, so 60 that they have an extended horizontal bearing in the horizontal holes in the shells n n' , so that the core-support is held from turning or swinging on the shells. The ends of the core-support are provided with one or more 65 aligned longitudinal holes n^4 , through which

tubes or rods n^5 (shown by dotted lines) are inserted when the core-support is placed in the core-box. When the core is formed in the box, the bottom portions thereof are supported and held together by the grate-bars of 70 the core-support, and the latter absolutely prevent the breaking or dropping off of portions of the core. After the core has been formed the tubes or rods n^5 are pulled out of their bearing-holes in the core-support and 75 leave longitudinal vent-holes in the core for the escape of gases, which pass out through these holes in the core and the holes in the ends of the core-support. The end portions of the core-support are preferably provided 80 with holes or made in skeleton form to reduce the weight of the support.

The hinge-lug for the lid of the car journal-box is formed by a baked-sand core O, Fig. 5, which constitutes a part of the whole completed core. This core part is supported in correct position on the core-box by a sectional horizontal slide or bridge, which rests on the upper edges of the sides of the core-box, and consists of a section P, provided with a longitudinal dovetailed or undercut groove p , and a section P', which slides in said dovetailed groove. The two sections of the slide are provided on their under sides with depending lugs p' , which make depressions p^2 , 90 Fig. 5, in the top of the core for molding the separated depending lugs on the inside of the top of the journal-box for retaining the journal-brasses in place. The lugs on the two parts of the slide engage in notches p^3 in the 95 upper edges of the sides of the core-box, which serve to properly position the slide and permit the passage of the lugs in separating the sections of the slide after the core is completed. The two sections of the slide 100 are provided at their outer ends with handles p^4 and are preferably provided with depending hooks or the like p^5 , Fig. 4, which engage under overhanging lips at the upper edges of the sides of the core-box to prevent the slide 105 from lifting when tamping the sand in the box.

In using the core-box to form a core the baked-sand core K for forming the dust-guard chamber and the bearing-shells n n' are placed 110 on the core-arbor, and the latter is placed in position on the base of the core-box, with its bearing-shells on the seats c d at opposite ends of the base. The sides F of the box are then 115 swung upwardly to their upright position and secured by the pivoted catches h at the ends of the box. The supporting-slides M for the dust-guard-chamber core are then inserted laterally through the openings in the sides 120 of the box. The sectional supporting-slides P P' for the core part for forming the hinge-lug is placed in position on the tops of the 125 sides of the core-box and the core part for the hinge-lug placed on the supporting-slide. The supporting-slide is so disposed and propor- 130

tioned that the core part will retain its position with a portion thereof projecting out from the supporting-slide. Sand is then put in the box and tamped or packed and struck off at the top in the usual manner. The slides for the dust-guard-chamber core and for the hinge-lug core are then removed by pulling the same laterally out of their retaining openings and notches and the sides of the box 5 are swung downwardly to a horizontal position. When the supporting-slide for the hinge-lug core is removed, the lug-core is supported in its proper position on the top of the main core and constitutes a part thereof. The core is 10 thus left exposed on the bottom or base of the core-box and can be lifted off of the base by means of the projecting ends of the core-support N. As the fillets which form the rounded upper and lower longitudinal corners of the 15 core are carried by the sides of the core-box they are moved with the sides away from the core and they cannot therefore strike and break the corners of the core in lifting the core off of the base. The core can be removed 20 from the base without any particular care being exercised, because there are no parts of the box which can strike the core and mar or break it. The hinge-lug mold, forming, as it does, a part of the core, cannot be misplaced 25 relative to the core when the latter is placed in the mold-flask, and the hinge-lug will necessarily be located properly on the journal-box.

In use the core-box can be placed directly 30 on the floor of the foundry or on a low support, as most convenient for the particular workman using the box. This is a great advantage over a machine in which the core is formed at a considerable height from the floor, 35 because less exertion is required for the workman in shoveling the sand into the box, and the core-box is at a desirable height for tamping the sand. Furthermore, when the core 40 has been completed and the box is opened, the core is in the most advantageous position for the workman to lift it off of the base, and the sides of the core-box do not occupy a position 45 which will prevent the workman from obtaining the necessary lifting purchase on the core.

50 In forming a core for a journal-box in which the front wall below the filling-opening inclines rearwardly it is desirable to provide a removable slide to form this portion of the front face of the core. Such a slide is shown 55 at R and is inserted transversely of the box in holes r in the sides of the core-box. The slide is provided with a projecting portion or handle by which it is inserted and removed 60 from its retaining-holes.

65 I claim as my invention—

1. In a portable box for making green-sand cores, the combination of a base having a forming-face conforming to the lower portion of the core to be made, and supporting portions 65 below said forming-face to rest on and ele-

vate said forming-face above a supporting-surface, and also having end supports for a core-arbor, oppositely-arranged sides having inner faces conforming to the opposite portions of the core to be made, said sides being 70 hinged adjacent to their lower edges directly to said base below said forming-face, whereby said sides can be swung downwardly away from the core to completely expose the latter without interfering with the workman in lifting the core off of said base, means for securing said sides in an upright position, retaining parts for an upright separate core fixed to and projecting inwardly from the upper portions of said sides, and retaining-plates 80 for said separate core projecting inwardly from the lower portion of said sides and removably supported thereby, substantially as set forth.

2. In a portable box for making green-sand cores, the combination of a base having a forming-face conforming to the lower portion of the core to be made, and having supporting portions below said forming-face to rest on and elevate said forming-face above a supporting-surface, and also having end supports for a core-arbor, oppositely-arranged sides having inner faces conforming to the opposite portions of the core to be made, said sides being 90 hinged adjacent to their lower edges directly to the base below said forming-face, whereby said sides can be swung downwardly away from the core to completely expose the latter without interfering with the workman in lifting the core off of said base, means for 95 securing said sides in an upright position, retaining parts for an upright separate core fixed to and projecting inwardly from the upper portion of said sides, said sides having vertical slots below said fixed retaining parts, and removable retaining-plates for said separate core projecting into the core-box through 105 said slots, substantially as set forth.

3. A core-box comprising a base provided with an upper face conforming to the lower face of the core to be formed, sides hinged at their lower edges to said base and having inner faces conforming to the side faces of the core, means for securing the sides in an upright position, inwardly-projecting separated 110 plates secured to the upper portions of said sides, and removable slides arranged below said inwardly-projecting plates in vertical openings in the sides of said box, substantially as set forth.

4. A core-box comprising a base provided with an upper face conforming to the lower face of the core to be formed, sides hinged at their lower edges to said base and having inner faces conforming to the side faces of the core, means for securing said sides in an upright position, a sectional horizontal slide extending across the core-box and supported by 115 said sides, and constituting a temporary support for a core part which is supported by the 120

core when said sectional slide is removed, substantially as set forth.

5. A core-box comprising a base provided with an upper face conforming to the lower face of the core to be formed, sides hinged at their lower edges to said base and having inner faces conforming to the sides of the core, means for securing said sides in an upright position, a sectional slide supported on the upper portions of said sides and having depending lugs which engage in notches in said sides, said sectional slide constituting a temporary support for a core part which is supported by the core when said sectional slide is removed, substantially as set forth.

6. A core-box comprising a base provided with an upper face conforming to the lower face of the core to be formed, sides hinged at their lower edges to said base and having inner faces conforming to the sides of the core, means for securing said sides in an upright position, a sectional slide supported on the upper portions of said sides and having depending lugs which engage in notches in said sides, said sectional slide constituting a temporary support for a core part which is supported by the core when said sectional slide is removed, and means for holding said sectional slide from raising off of its supports, substantially as set forth.

7. The combination of a core-support comprising end portions which rest on suitable supports on the core-box, and integral bars which connect said end portions and extend downwardly between the end portions to support the lower portion of the core, said end portions having one or more longitudinal-alined holes and a rod or tube removably held in said holes and which when removed leaves a vent-hole in the core, substantially as set forth. 35

8. The combination of a core-box provided at opposite ends with seats, bearing-blocks resting on said seats and provided with longitudinal holes, a core-support comprising end portions removably engaged in said seats in the bearing-blocks and having one or more integral bars connecting said end portions and extending downwardly between the same to support the lower portion of the core, said end portions of the core-support having longitudinal-alined holes and one or more rods removably held in said holes and which when removed leave vent-holes in the core, substantially as set forth. 45 50
